UNITED STATES PATENT OFFICE.

GRAHAM CLARKE, OF CLEVELAND, OHIO, ASSIGNOR TO THE OHIO CHEMICAL AND MANUFACTURING COMPANY, OF CLEVELAND, OHIO, A CORPORATION OF OHIO.

ATTACHMENT FOR ANESTHETIZING APPARATUS.

1,068,628.

Specification of Letters Patent.

Patented July 29, 1913.

Application filed July 5, 1912. Serial No. 767,678.

To all whom it may concern:

Be it known that I, GRAHAM CLARKE, a citizen of the United States, residing at Cleveland, in the county of Cuyahoga and

5 State of Ohio, have invented a certain new and useful Improvement in Attachments for Anesthetizing Apparatus, of which the following is a full, clear, and exact description.

10 This invention is a desirable adjunct of an anesthetizing apparatus; and it is designed to serve two useful purposes, viz., first, to heat the anesthetizing gas, such as nitrous oxid, or air, or some admixture of 15 the two, as it flows, under pressure, to the face mask from tanks in which said gas is stored; and second, to enable the operator to produce and administer ether vapor whenever desired and in a manner thor- 20oughly under control.

The invention is constructed so that it may be easily and quickly connected with the conduit leading from the gas and air tanks, on the one hand, and with the flexible 25 tube leading to the face mask, on the other hand.

In the drawing, Figure 1 is a vertical sectional view of a device embodying the invention. Fig. 2 is a view partly in central 30 section in a plane at right angles to the section on which Fig. 1 is taken. Fig. 3 is a horizontal section in the plane of line A—A on Fig. 2.

The body of the device includes the following parts which are preferably made integral with one another, viz., the inlet tube 3 which is adapted for connection with the supply of gas and air, the outlet tube 4 adapted for the attachment thereto of the 40 gas delivery tube which has the face mask on its free end; and the centrally placed ether vaporizing cup 5. This cup has no connection with the inlet tube 3, but does communicate with the outlet tube 4 through 45 the hole or port 6 in the wall of said cup. On this body is a downwardly extended cylindrical flange 7 concentrically arranged around the ether cup, which flange is internally threaded. The water receptacle 8 50 is externally threaded at its upper end and screws into this flange, whereby it is suspended from the body. This water receptacle has a centrally placed reentrant cham-

ber 9 which is open at its lower end so that it may receive and hold an electric heating 55 coil 10 of any suitable construction.

Within the water receptacle and around this tube 9 are two annular hollow headers 12 and 13 and extending between them are numerous vertical pipes 11 through which 60 they are placed in communication. A pipe 14 which is fixed to the inlet tube 3 passes through the upper header and is fixed to the lower header. Another pipe 16 is connected with the upper header and to the 65 outlet tube. The water receptacle has near its upper end a capped opening 15 through which the water may be introduced, and it has at its lower end a pet cock 17 through which the water may be withdrawn. 70

The ether vaporizing cup 5 at its lower end extends downward far enough to project into the water in the water receptacle 8. Fixed to the upper end of the ether vaporizing cup is the neck 20 of the ether 75 holder 21. This holder has in its bottom a nozzle 22 which is provided with a needle valve 23 to control the size of the delivery opening therethrough; and the neck has a window 24 through which the operator may 80 observe the rapidity with which the ether drops fall from said nozzle.

When this device is being used to heat nitrous oxid gas or air or any mixture thereof, said gas will flow into the inlet tube 3, 85 thence through tube 14 into the lower header 13, thence through the numerous vertical tubes 11 into the upper header, and thence through pipe 16 into the outlet tube 4. The water in the receptacle will be kept at the 90 desired temperature by means of the electric heating coil 10, and therefore this gas will be properly heated as it travels the path above pointed out.

If, at any time, it is thought necessary or 95 desirable to administer ether to a patient, the valve 23 is opened sufficiently, and the ether allowed to flow, drop by drop from the nozzle 22. These drops will fall upon the bottom of the ether vaporizing cup 5, which, 100 because it is immersed in the warm water will be at such a temperature that this ether will immediately flash into vapor, and this vapor will flow into the outlet tube 4 through the port 6, and while in this tube 105 will become mixed with the air which

should be allowed to flow into the outlet tube 4, passing through the gas heater before described.

Having described my invention, I claim:

- 5 1. The combination of a body which includes as integral parts an inlet tube, an outlet tube, an intermediately placed cup which is in communication with the outlet tube only and which projects below said tubes, and a depending flange around said cup, with a water receptacle suspended from said flange, means for heating water in said receptacle, means for delivering ether drop by drop into said cup, and a conduit which extends down into said water receptacle and is connected at its ends respectively with the inlet tube and the outlet tube.
- 10 2. In an attachment for anesthetizing apparatus, the combination of a body member

having as integral parts an inlet tube, an outlet tube and an intermediately placed ether cup which extends below said tubes and is in communication with the outlet tube only, a hot water receptacle suspended 25 from said body around said ether cup, means for heating water therein, a conduit which is located in the water receptacle and is connected at its ends with the inlet and outlet tubes respectively, and an ether dropper supported by said body member and arranged to deliver ether drop by drop onto the bottom of said ether cup.

In testimony whereof, I hereunto affix my signature in the presence of two witnesses. 35

GRAHAM CLARKE.
